UNITED STATES PATENT OFFICE.

CYRIL G. SINCLAIR, OF TORONTO, ONTARIO, CANADA, ASSIGNOR, BY MESNE ASSIGNMENTS, TO RELIANCE STORAGE AND WAREHOUSE COMPANY, OF DETROIT, MICHIGAN, A CORPORATION OF MICHIGAN.

WASHING MACHINE.

Application filed May 22, 1924. Serial No. 715,103.

My invention relates to improvements in washing machines.

The general structure of the washing machine disclosing my invention which is herein described and claimed is more thoroughly set forth in my co-pending application Serial Number 715,102 this day filed which relates primarily to the construction and operation of the driving mechanism.

10 An object of my invention is to provide in a washing machine having a vat in which is disposed a rotatable tub adapted to serve as a washing tub and a centrifugal drying tub, means whereby certain drainage of the tub 15 may be collected in the vat for further use and other drainage of the tub may be discharged exterior of the vat, such discharge being in large part through the same channels.

20 An important object is the provision of a suitable tub for the above purpose which when slowly rotatably oscillated carries without any substantial loss the water contained therein, yet when rapidly continuously rotated throws off the water from the contained clothes.

25 An important feature is the provision in such a tub having discharge apertures of hoods formed on the inner surface of the tub, which hoods cover such discharge apertures, such tub being also preferably provided on its exterior surface with hoods over the discharge apertures, which hoods open downwardly to direct the water passing 35 through the apertures into a drainage collector surrounding the tub.

30 A novel part of the tub is the provision of an overhanging rim flange. A plurality of spaced-apart upright fins extend inwardly from the flaring side wall of the tub and the bottom is provided with a plurality of radially extending corrugations.

35 The above objects and others, together with other important structural elements, will more fully appear from the following description, accompanying drawings, and appended claims in which my invention is defined.

In the drawings,—

50 Figure 1 is a vertical cross-sectional view through my improved washing machine.

Fig. 2 is a horizontal sectional view taken on line 2—2, Fig. 1.

Fig. 3 is a fragmentary vertical sectional

view taken at right angles to the view in Fig. 1.

Fig. 4 is a fragmentary sectional view taken on line 4—4 of Fig. 3.

Fig. 5 is a fragmentary sectional view taken on line 5—5 of Fig. 2.

Fig. 6 is a vertical sectional view taken on line 6—6 of Fig. 2.

Fig. 7 is a sectional view taken on line 7—7 of Fig. 6.

My improved washing machine has a frame 10 suitably supported by legs 11 which carries a vat 12 having a depending skirt 13 and a removable cover 14. A motor 15 supported below the frame has a drive shaft 16 upon which is mounted a friction driving cone 17 which engages a friction disk 18 carried by a driven shaft 19 which shaft extends upwardly axially through the vat having a bearing for support in a standard 20 of the frame 10. A protective shroud 21 encloses the standard 20 and suitable packing 22 may be inserted between the shroud and the standard. The shaft is provided at its upper end with splines 23 to engage a removable cone clutch 24 to rotate therewith.

I provide a tub 25 which has a female cone clutch 26 provided with suitable recesses 26^a to engage lugs 27 on the removable male clutch member 24 so the tub when seated thereon will rotate therewith. The removable clutch member 24 and the weight of the tub is carried on a bearing 28 which rests on the upper end of standard 20.

The tub is provided with an upwardly outwardly-flaring side wall 29 which has an overhanging rim flange 30, a crown plate 31 being shown as extending over this rim flange. The side wall of the tub is provided with a plurality of spaced-apart upright inwardly-extending fins 32 and the bottom of the tub has a plurality of radial corrugations 33 and a drainage plug 34. The corrugations in the bottom of the tub and the fins on the side wall facilitate the washing operation.

The tub is supported upon the removable clutch member 24 as is shown in Figs. 1 and 6, and is secured thereto by a removable plug 48 which is threaded into the enlarged end portion of the axial passageway through the member 26. A spring 49 is held under compression against the end of shaft 19 by this plug 48.

As described in my co-pending application,

the tub is adapted to be slowly rotatably oscillated or rapidly continuously rotated. During the slow rotatable oscillatory movement the clothes are washed. During the 5 movement of rapid continuous rotation the water is expelled from the clothes.

In order that the tub may serve both purposes I provide in the upper portion of its side wall in proximity the overhanging flange 10 30 a plurality of apertures 34. These apertures are arranged at intervals around the wall of the tub. Over each aperture or group of apertures I provide interior the tub a hood 35 which extends between the side wall 15 of the tub and the overhanging flange. This hood extends circumferentially the tub and is open only at one end. On the outside of the tub I provide a hood 36 which extends over the apertures 34 and is open at the 20 bottom to direct the discharge through the apertures downwardly.

There is provided an annular drainage collector 37 in the form of a flange carried by the side wall of the vat and surrounding the 25 tub below the discharge apertures therein. This drainage collector is adapted to collect the drainage from the tub. It has an outlet pipe 38 which has a branch 39 that leads to an overflow bowl 40 and a branch 41 extending through the wall of the vat to discharge exterior thereof. A manually operable gate 42 is provided to regulate the flow of the water. When this gate is closed the water from the outlet pipe will enter the bowl and 30 overflow into the vat. When the gate is open the water will discharge exterior the vat. This overflow bowl is so situated with respect to the tub that the tub may be rotated to bring the plug opening 34 into position 35 to discharge into the bowl.

I provide a rotary pump 43 which is driven from the motor shaft by means of a clutch 44 controlled by a shifter fork 50 actuated by a manually operable lever 51, as described 45 in my co-pending application. This pump has an inlet 45 to receive water from the vat and a discharge outlet 46 which terminates in a swinging spout 47 adapted to be moved to discharge into the tub or into a suitable receptacle exterior the tub.

At the completion of a washing operation the tub may be rapidly rotated and the suds discharged into the collector 37 and drained into the bottom of the vat overflowing from the bowl 40, which will result if the gate 42 is closed, or the plug 34 may be removed and the suds water drained directly into the vat. The clothes are permitted to remain in the tub and rinsing water is placed in the tub, 50 after which the tub is rapidly continuously rotated to rinse the clothes and the water discharged through the apertures 34 into the collector 37. The gate 42 is now open and this rinsing water discharges exterior the vat. The overflow bowl is at such a height 55

and the size of the discharge spout is such that this result will occur. The clothes are now removed from the tub and a second washing of clothes is placed in the tub and the pump operated to draw the suds from the vat 70 back into the tub and the washing operation repeated. In this manner the same suds may be employed to wash several tubsful of clothes while the rinsing water is discharged free of the vat without intermingling with the suds. 75

In Figs. 6 and 7 I have shown in connection with my tub 25 a supplemental tub 52 perforated as at 53. This tub is considerably smaller than the tub 25 and is adapted to be received therein and seats over the upwardly-extending conical member 26 of the tub 25. This conical member 26 has formed on its outer surface a plurality of ribs 54 adapted to engage with corresponding recesses 55 formed in the under surface of the bottom of the tub 52. A securing plug 56 is threaded into the enlarged end of the axial opening through the member 26 and holds under compression the spring 49 to yieldingly resist the upward movement of shaft 19 and at the same time holds the tub 52 upon the conical member 26. This tub 52 is adapted to receive a relatively limited number of clothes centering them about the axis of revolution of the tub 25, thereby minimizing the vibration 95 of the tub during its rotation.

What I claim is:

1. In a washing machine, a vat, a tub rotatably supported therein, said tub having an overhanging rim flange, a discharge aperture through the wall of the tub in proximity to said flange, a hood extending between the wall of the tub and said flange over said aperture, said hood being open at one end.

2. In a washing machine, a vat, a tub rotatably supported within the vat, said tub having a discharge aperture in the upper portion of its side wall, a hood extending circumferentially interiorly of the tub over 100 said aperture, said hood being closed at one end and open at the opposite end.

3. In a washing machine, a vat, a tub rotatably supported within the vat, said tub having a discharge aperture in the upper 115 portion of its side wall, a hood extending circumferentially interiorly of the tub over said aperture, said hood being closed at one end and open at the opposite end, and a hood over said aperture on the exterior of the tub.

4. In a washing machine, a vat, a tub rotatably supported within the vat, said tub having an overhanging rim flange, a discharge aperture through the wall of the tub in proximity to said flange, a hood extending 125 circumferentially interiorly of the tub over said discharge aperture, said hood extending between the wall of the tub and the rim flange and flaring circumferentially of the tub toward an open end.

5. In a washing machine, a vat, a tub rotatably supported within the vat, said tub having a discharge aperture in the upper portion of its side wall, a hood extending circumferentially interiorly of the tub over said aperture and flaring toward an open end, a deflector extending from the outer wall of the tub over the aperture and being open at the bottom to direct the discharge through the 10 aperture downwardly.
6. In a washing machine, a vat, a tub rotatably supported within the vat, said tub having a discharge aperture through the upper portion of its side wall, a hood extending 15 from the inner surface of the side wall of the tub and circumferentially of the tub over said aperture, said hood being open at one end, a hood extending from the outer surface of the side wall of the tub downwardly 20 over said aperture and being open at the bottom.
7. In a washing machine, a vat, a tub rotatably supported within the vat, said tub having a discharge aperture in the upper 25 portion of its side wall, a hood extending from the outer surface of the side wall over said aperture and having a discharge opening at the bottom.
8. In a washing machine, a vat, a tub rotatably supported within the vat, said tub having a discharge aperture through the upper portion of its side wall, a hood extending 30 from the inner surface of the side wall of the tub and circumferentially of the tub over said aperture, said hood being open at one end, a hood extending from the outer surface of the side wall of the tub downwardly over said aperture and being open at the bottom, and an annular drainage collector carried by the vat surrounding said 35 tub to catch the discharge therefrom.
9. In a washing machine, a vat, a tub rotatably supported within the vat, said tub having a discharge aperture through the upper portion of its side wall, a hood extending 40 from the inner surface of the side wall of the tub and circumferentially of the tub over said aperture, said hood being open at one end, a hood extending from the outer surface of the side wall of the tub downwardly over said aperture and being open at the bottom, and an annular drainage collector carried by the vat surrounding said 45 tub to catch the discharge therefrom, said drainage collector having an outlet adapted to discharge into the vat and an outlet capable of discharging exterior the vat, and means for regulating such discharge.
10. In a washing machine, a vat, a tub rotatably supported within the upper portion 50 of the vat, said tub having an upwardly outwardly-flaring side wall provided with an overhanging rim and having a bottom provided with a plurality of upwardly-projecting radial ribs, said side wall provided with 55 a plurality of upright inwardly-extending fins, the side wall of said tub having a plurality of spaced-apart apertures disposed in proximity to the rim, a hood extending circumferentially of the tub over each of said apertures, said hood extending between the side wall of the tub and the rim thereon and being open at one end only, water-deflecting hoods secured to the outer surface of the tub over each of said apertures and open at 60 the bottom to direct the discharge through the apertures downwardly, and an annular flange extending inwardly from the vat about the tub to catch the discharge therefrom.
11. In a washing machine, a vat, a tub rotatably supported within the upper portion 65 of the vat, said tub having discharge apertures in its side wall, said vat provided with a drainage collector surrounding the tub to gather the discharge therefrom, said drainage collector having an outlet provided with a discharge leading into the vat and an outlet adapted to discharge exterior of the vat, and means for regulating the flow through 70 said outlets to cause the discharge to flow through either of said outlets to the exclusion of the other, said discharge opening leading to the interior of the vat terminating in a bowl, said tub provided with an independent discharge opening adapted to be moved into 75 position to discharge into said bowl.
12. In a washing machine, a vat, a tub mounted for rotation within said vat, said tub having an upwardly projecting axial portion, a smaller supplemental perforated tub 80 adapted to be removably seated for support upon said axial portion, said axial portion and bottom of the supplemental tub having engaging portions adapted to lock the supplemental tub to rotate with said axial portion. 85
13. In a washing machine, a vat, a perforated tub rotatably mounted therein, an annular drainage collector within the vat and surrounding the tub adapted to catch the centrifugal discharge of the tub, said drainage 90 collector having an outlet adapted to discharge exteriorly of the vat and a discharge outlet which terminates in a basin interior of the vat. 95
14. In a washing machine, a vat, a perforated tub rotatably mounted therein, an annular drainage collector within the vat and surrounding the tub adapted to catch the discharge therefrom, said drainage collector having an outlet adapted to discharge exteriorly of the vat, a basin within the vat 100 communicating with the outlet of the annular drainage collector to discharge therethrough, said tub provided with an independent outlet for drainage adapted to be brought into position to discharge into said basin. 105
15. In a washing machine, a vat, a perforated tub rotatably mounted therein, said vat provided with a drainage collector adapted to catch the centrifugal discharge of the 110

- tub and prevent the same from falling into the vat, said drainage collector having an outlet adapted to discharge exteriorly of the vat, said tub provided with an independent outlet, 5 said vat provided with a second drainage collector adapted to catch the discharge from said independent outlet of the tub, and discharge the same exteriorly of the vat.
16. In a washing machine, a vat, a perforated tub rotatably mounted therein, said vat provided with a drainage collector adapted to catch the centrifugal discharge of the tub, said tub provided with an independent outlet for drainage, said vat provided with 10 a second drainage collector adapted to catch the discharge from said independent outlet of the tub.
17. In a washing machine, a vat, a perforated tub rotatably supported therein, said 15 vat provided with a drainage collector adapted to catch the centrifugal discharge of the tub and adapted to discharge the same either into the vat or exteriorly thereof, said tub provided with an independent outlet for 20 drainage, said vat provided with a second drainage collector adapted to catch the discharge from said independent outlet of the tub and discharge the same either into the vat or exteriorly thereof.
18. In a washing machine, vat, a clothes basket rotatably supported within the vat, said basket having a perforated side wall through which its contents may be centrifugally discharged upon rotation and a second discharge opening through which its 25 contents may be drained; an independent drainage collector within the vat adapted to catch the centrifugal discharge of the basket through its perforated side wall and having a portion adapted to catch the drainage of 30 the basket through its second discharge opening.
19. The invention set forth in claim 18 including means whereby the independent drainage collector may be drained into the vat or exteriorly thereof.
20. In a washing machine, a vat, a clothes basket rotatably supported in the upper portion of the vat, said basket having a perforated side wall for the centrifugal discharge of its contents upon rotation of the basket and a controlled independent drainage outlet in the bottom of the basket; an independent annular drainage collector within the vat extending inwardly from the side wall and adapted to catch the centrifugal discharge of the basket and prevent the same from falling into the vat, said drainage collector having a portion adapted to catch the discharge 40
- of the basket through the independent drainage outlet in the bottom of the basket, said drainage collector provided with means whereby its contents may be discharged either into the vat or exteriorly thereof.
21. In a washing machine, a vat, a tub rotatably supported therein, said tub having an overhanging rim flange, a discharge aperture through the wall of the tub in proximity to said flange, a hood extending from the wall of the tub over said aperture.
22. In a washing machine, a vat, a tub rotatably supported therein, said tub provided with a discharge aperture through the upper portion of its side wall, a hood extending from the wall of the tub over said aperture.
23. In a washing machine, a vat, a tub rotatably supported within the vat, said tub having a discharge aperture in the upper portion of its side wall, a hood open at one end extending from the wall of the tub over said aperture on the interior of the tub, a hood open at the bottom extending from the wall of the tub over said aperture on the exterior of the tub.
24. A washing machine having a vat provided with a drainage collector projecting inwardly from its side wall and extending circumferentially thereof, a tub provided with an upwardly outwardly flaring side wall perforated near its upper edge only and supported within the vat to extend above and below the drainage collector and to overhang such collector so that the perforations of the tub are above the collector, said tub supported within the vat for rotatable oscillation or rapid continuous rotation, means for rotatably oscillating or continuously rotating the tub, said drainage collector provided with an outlet whereby its contents may be discharged either into the vat or externally thereof.
25. A washing machine having a vat provided with a drainage collector projecting inwardly from the side wall of the vat and extending circumferentially thereof, a tub rotatably supported within the vat to extend above and below said drainage collector, said tub provided with an outlet below the level of the drainage collector through which the contents of the tub may be discharged directly into the vat and provided with a second outlet above said drainage collector through which the contents of the tub will be centrifugally discharged upon rotation of the tub into said drainage collector only.

In testimony whereof, I sign this specification.

CYRIL G. SINCLAIR.
